Primary Examiner — Paula Allen Greene(74) *Attorney, Agent, or Firm* — Cooley LLP(57) **CLAIM**

The ornamental design for headphones, as shown and described.

DESCRIPTION

FIG. 1 is a perspective view of embodiment of the headphones;

FIG. 2 is a front view of the embodiment;

FIG. 3 is a back view of the embodiment;

FIG. 4 is a left side view of the embodiment;

FIG. 5 is a right side view of the embodiment;

FIG. 6 is a top view of the embodiment; and,

FIG. 7 is a bottom view of the embodiment.

The broken lines immediately adjacent the shaded areas represent the bounds of the claimed design while all other broken lines are directed to environment and are for illustrative purposes only; the broken lines form no part of the claimed design.

1 Claim, 7 Drawing Sheets(56)
